RADIO FREQUENCY COIL WITH SUBDIVIDED
IRON CORE

Otto Wohlfarth, Berlin, and Alfred Agricola, Berlin-Tempelhof, Germany, assignors to Allgemeine Elektricitat Gesellschaft, Berlin, Germany

Application May 7, 1935, Serial No. 20,160
In Germany May 7, 1934

4 Claims. (Cl. 171—119)

The present invention relates to radio frequency inductance coils and more particularly to such coils which are provided with powdered magnetic material cores.

5 Radio frequency coils are known in the prior art which are furnished with subdivided iron-cores, more particularly iron-cores made of compressed or molded iron powder. Coils of this kind, if the iron powder has been chosen properly and also the insulation thereof, when compared with air-cored coils, are of smaller dimensions for the same loss. Another merit of coils of this kind consists in that they have less leakage or stray than air-cored coils.

15 Now, it has been found that with the application of well known ways and means in making the iron-cores, i. e., extensive subdivision of the iron-core (grain size less than 10μ) the iron-losses may be diminished to such a point where 20 their share in the total losses becomes so small that the losses occasioned in the coil and which are a function of the frequency, especially capacitive losses and eddy-current losses, exercise a decisive influence upon the quality of the iron-cored coils. So far as the quality of the radio 25 frequency coil, especially its use in tuning circuits covering a comparatively extensive frequency range or band is concerned, for instance, the range included in broadcast waves, it is important that the frequency-dependent portion of 30 the coil losses should be as low as possible in order that the ratio $R:\omega L$ will be stable and constant as far as feasible for the frequency range here concerned (where R = dielectric loss angle, L inductance, and ω = frequency, 2π).

35 As has been borne out by experiments of which this invention is the outcome, these losses are essentially affected by the shaping and the selection of the material for the coils. Iron-cored 40 coils as known in the prior art have mostly been of the kind with a cylindrical and a disk winding. Both these types of winding, when employed in connection with iron-cored coils, involve the demerit that turns which have alternating voltage are directly adjacent the iron core.

45 Now, according to this invention the winding is built up in such a fashion that the turns carrying alternating voltage are so much farther removed from the iron core, the higher such alternating voltage applied to them, the winding being at the same time so chosen that it will inherently be of low capacitance. The losses by virtue of capacitive leakance will then be found 50 to be particularly low, and a coil thus designed

exhibits substantially lower losses than the coils so far used in combination with iron-cores.

5 In the drawing, Fig. 1 illustrates one form of the invention wherein a cross wound coil is provided with a core; Fig. 2 illustrates diagrammatically the formation of the wire used to wind the coil; Fig. 3 is a curved sheet illustrating the characteristics of the coils; Fig. 4 is a modification of the coil structure shown in Fig. 1 and Figs. 5 and 6 illustrate diagrammatically certain 10 preferred embodiments of the invention.

15 The coil of the invention may be designed in the form of a cross-wound coil the end of which located towards the iron-core is connected with a fixed potential (grounded). The form of the 20 coil in this scheme is preferably so chosen that its width b will be several times the length l as shown in Fig. 1.

25 The cross-winding offers over the coil known in the art a chance for using the coil unsupported, that is to say, without the use of a bobbin or coil body. This insures the advantage that the inside cross-sectional area of the coil winding is completely filled by the iron-core s (Fig. 1) with the result that the field of force set up in 30 the interior of the coil is homogeneous, and this means a further reduction of the losses.

35 According to another object and idea of this invention, with a view to reducing the frequency dependent coil losses still further, recourse is had to a multiple subdivision of the strands used for the winding, in other words, the wire of the coil consists of a multiple-stranded litz. The latter, for instance, could be composed and built up in such a way that several, say, three strands or 40 litzes each of which consists of three or more inter-stranded constituent or individual conductors, are in turn twisted or stranded together as shown in Fig. 2, where a_1 , a_2 , a_3 , designate three strands each of which is composed of three individual conductors, and these three strands are again twisted or stranded together. By such multiple stranding the losses due to skin effect 45 are substantially diminished.

45 In a form of coil as stated it is also possible to choose the diameter of the constituent conductors of the strand extremely small so that both the eddy-current losses in the strand proper as well as the capacitive losses of the coil will be 50 reduced. At the same time, the increase in the ohmic resistance of the coil due to the reduction in the cross-sectional area of the wire, and which is independent of the frequency, has a favorable effect. As can be seen from Fig. 3, the simultaneous increase in the ohmic resistance which 55

plays a large part in the aggregate coil losses especially where low frequencies are dealt with, leads to a further flattening of the loss curve. The curve *e* which stands for a coil made of comparatively stout wires and multiple-stranded litz, changes over to curve *f* when using a coil made of slender wires and multiple subdivision of the strand, for the same number of conductors. Curve *f*, it will be noted presents a far 10 flatter form, with the result that the ratio

$$\frac{R}{\omega L}$$

throughout the frequency band becomes considerably more constant.

Very favorable results were obtained with strands of $3 \times 6 \times 0.05$ mm., in other words, strands in which the constituent wires or conductors consist of copper wire with a cross-section of only 0.05 mm., six of which were twisted together so that there resulted three strands which were, in turn, stranded together.

For the purpose of a further reduction of the frequency-dependent losses the strand, according to the invention is lined with one or more coats or layers of low-loss insulation material, such as low-loss paper, say, Japanese paper. In this manner spacing between the constituent spires of the coil is insured so that the field set 20 up around the strand axis and which decreases rapidly with the distance will cut across the adjacent strands only to a limited extent.

The reduction of the losses attainable by choosing a coil form as hereinbefore disclosed is 35 still further decreaseable by shaping the iron body or core in a suitable way. In the iron-cored coils known to the earlier art, the said iron body mostly presents the form of an *H* or of a ring. These forms inhere quite a number of disadvantages, *inter alia*, that the winding and thus live 40 portions of the coils come to be placed at close proximity to the iron core, and this is conducive to additional coil losses. In order to reduce losses of this kind, according to another basic 45 idea of the invention the said iron-core is so formed and disposed in reference to the coil that the live parts of the coil are spaced apart from the iron core. It is advantageous in this connection to give the iron core the shape of a body 50 of rotation.

Exemplified embodiments are shown in Figs. 4 to 6. Fig. 4 shows an iron-cored coil which consists of winding *w* which has the shape of a cross-winding, and the iron core comprising 55 parts *s*₁ and *s*₂. These parts *s*₁ and *s*₂ are cup-shaped bodies presenting rotational symmetry and whose bottom surfaces interengage. The supply-lead *z*₁ on the iron body is grounded, while the opposite lead *z*₂ is on voltage.

As can be seen the edges of the cups are so bent away from the winding *w* that those parts of the winding which are at a higher potential are farther removed from the iron body than the portions being at a lower potential.

The fact that the iron body is cup shaped insures an adequately closed magnetic path. But in order that the entire magnetic path may be improved, the cups *s*₁ and *s*₂, as shown in Fig. 5 may at the outermost edge *r* be again bent towards one another. In this manner also the stray is diminished. If desired, as shown in Fig.

6, the edges of the cups could also be completely closed. This means a further advantage in that the coil *w* is screened at the same time. If, as shown in Fig. 5, the two halves of the cups or shells are placed flatly against each other, then the bottom of the same, and, if desired, also the edges of the same, could be made elliptical instead of presenting rotational symmetry so that by turning the two cups *s*₁ and *s*₂ in reference to each other it is possible to alter the inductance 10 of the coils, a fact, that may be of advantage in matching or adapting coils.

We claim:

1. A radio frequency coil provided with a core composed of compressed finely divided magnetic material, said core comprising a pair of adjacent cooperating cup shaped members arranged with respect to each other so as to form an enclosure for the coil, one of said members being provided with a central abutment upon which the coil is wound, said abutment being placed on the side of the cup shaped member which is adjacent the other cup shaped member.

2. A radio frequency coil provided with a core composed of compressed finely divided magnetic material, said core comprising a pair of adjacent elliptical cup shaped members mounted with respect to one another so as to form a substantial enclosure for the coil, one of said members being provided with a central abutment on the inside portion thereof, the coil being supported upon said abutment, said two members being displaceable relative to one another to thereby provide means for varying the inductance value of the coil.

3. In an inductance device, a coil, a magnetic material core for the coil, said core comprising two shell halves, one of said shell halves being provided with a pin, said coil being positioned around the pin, the other shell half having formed therein a recess for receiving the pin of the other shell half, said shell halves being constructed so that a substantial portion of the outer peripheries thereof are a greater distance from the pin and recess respectively than another substantial portion of the outer peripheries thereof, whereby the inductance of the coil may be varied by rotating one of the shell halves with respect to the other thereof.

4. A high frequency coil provided with a core composed of compressed finely divided magnetic material, said core comprising a pair of adjacent cooperating cup-shaped members arranged with respect to one another so as to form a substantially closed magnetic path, one of said members being provided with a central abutment, said coil being cross wound around said abutment, the radial diameter of the coil being several times its length, leads for connecting the coil to external circuits, one of said leads being on the outer periphery of the coil, the other thereof being connected to the coil at a point which is near the abutment, said last named lead being grounded when the core is connected to an external circuit, the other lead being connected to a point of comparatively high voltage whereby the turns of the coil carrying the greater voltage are furthest away from the abutment.
